SCISSOR TYPE ELEMENT FOR REMOVING
DENTS FROM BODY AND FENDER PANELS

Francis G. Forster, Ecorse, Mich.

Application April 12, 1948, Serial No. 20,414

2 Claims. (Cl. 153—39)

1

This invention relates to metal working tools, and particularly to a tool for drawing out and straightening panels when disposed adjacent to each other.

Various means have been provided heretofore in the art for drawing and straightening panels, such as those of automobile bodies when deformed. Such structures, however, have usually been of such size that they could not be applied to panels when disposed close together.

The present invention pertains to a pair of pivoted arms, the unpivoted ends of which are disposed in close adjacent relationship to each other and capable of being spread apart by power means applied between the two arms for forcing one panel outwardly from another. The arms are so constructed as to permit the use of standard pressure applying equipment, such as a cylinder having a piston therein, between the arms. A hand-operated pump may be employed for forcing fluid into the cylinder to move the piston outwardly and the arms apart at the unpivoted end for pushing the crumpled panel outwardly to its initial position.

Accordingly, the main objects of the invention are: to provide a pair of arms pivoted at one end, with means for supporting a pressure applying element therebetween for moving the unpivoted ends apart; to provide a pair of pivoted arms with an abutment for a pressure applying device spaced from the pivot to provide a moment arm capable of moving the unpivoted ends of the arms apart for performing work on a panel to be straightened when force is applied thereto; and, in general, to provide a pair of pivoted arms for straightening panels which is simple in construction and economical of manufacture.

Other objects and features of novelty of the invention will be specifically pointed out or will become apparent when referring, for a better understanding of the invention, to the following description, taken in conjunction with the accompanying drawing, wherein:

Figure 1 is a view in elevation of a device for straightening panels embodying features of this invention;

Fig. 2 is a plan view of the structure illustrated in Fig. 1; and

Fig. 3 is a view of structure, similar to that illustrated in Fig. 1, showing a modified form thereof.

Referring to Figs. 1 and 2, a panel straightening device 10 of the present invention is illustrated, embodying an arm 11 made of two parallel side bars 12 and 13, the working performing ends

2

of which taper toward each other at 14 where they are connected by a threaded nut or boss 15. The arms are connected centrally of the ends by a plate 16 and at the end opposite from that connected by the nut 15 by a cross bar 17 welded thereto. The bar 17 has an element 18 welded or otherwise secured thereto, having a head 19 for a purpose which will be explained hereinafter.

A second arm 21 is made of two parallel side bars 22 and 23 which nest within the bars 12 and 13 along the parallel portion and which are tapered at 24 to nest within the tapered portion 14 of the bars 12 and 13. The arms are interconnected at the tapered ends by threaded nuts or bosses 25 adjacent to the middle portion by a bar 26 having a boss 27 thereon containing an aperture 28 and at the opposite ends by a bar 29. A bolt 31 extends through the arms at a point remote from the head 19 so that the distance between the head 19 and the bolt 31 provides a moment arm for a pressure element 32 which applies a force between the head 19 and boss 17. This forces the free ends of the arms 11 and 21 away from each other.

The element 32 is of conventional form, embodying a cylinder 33 having an aperture 34 in the end which extends over the head 19 and having a piston 35 projectable from the opposite end and having a stud 36 thereon which projects within the aperture 28. The device 32 is retained in position by the engagement of the head 19 in the aperture 34 and the engagement of the stud 36 in the aperture 28. Any means may be provided for applying a fluid to the cylinder 33, a hand-operated pump 37 being herein illustrated as being connected to the cylinder by the flexible conduit 38.

Universally movable heads 39 have a ball and socket connection with a stud 41 and are threaded into the threaded apertures in the nuts or bosses 15 and 25. A plate 42, having a stud 43 therein, may be threaded into the head 39 to enlarge the surface thereof when it is desired that a larger surface than that of the head be employed for pushing out the panel to prevent it from being further distorted. The arms, when in collapsed position, have the heads 39 on the unpivoted ends disposed in close relation to each other so as to fit into a narrow space. When using the device, the head 39 is inserted between the panel to be pressed out and an adjacent panel, brace or other rigid element, and pressure is then applied to the device through the introduction of fluid pressure into the cylinder 33 to force the head 39 on one

arm outwardly of the other to move the distorted panel outwardly to its original position.

A further form of the invention is illustrated in Fig. 3 which is somewhat similar to that illustrated in Figs. 1 and 2, with the exception that the pressure applying means is disposed beyond the length of the arms 11 and 21 instead of therebetween as described. One arm 45 is made up of two side plates 46, interconnected by suitable bracing elements 47 and 48, the latter of which is provided with a head 49 for receiving the apertured end of the device 32. The forward end of the plates 46 taper toward each other to engage a threaded nut or boss 51 which is welded thereto. A movable arm 52 is made of two plates 53 spaced apart by bracing elements 54 and 55, the latter of which is provided with a boss 56 having an aperture 57 therein. The forward ends of the plates 53 taper toward each other at 58 and are joined by a threaded nut or boss 59 which is welded thereto. The nuts or bosses 51 and 59 receive the threaded studs 41 for supporting the heads 39 for universal movement thereon. It is to be understood that the plates 42 may be applied to the head 39, the same as on the head or heads 39 of the device illustrated in Fig. 2.

A bolt 61 extends through the plates 46 and 53 remote from the aperture 57 so as to provide a lever arm equal to the distance between the bolt and aperture. The device is operated in the same manner as that described for the device illustrated in Figs. 1 and 2, the arm 52 being collapsed against the arm 51 with the heads 39 disposed adjacent to each other so as to be insertable in a narrow space between a distorted panel 35 and a rigid element against which pressure may be applied to move the panel outwardly to its original position. This is accomplished by applying fluid pressure to the cylinder 33 for moving the piston 35 outwardly to cause the arm 52 to move outwardly from the arm 45.

What is claimed is:

1. In a device for pushing and straightening panels, a pair of channel-shaped arms of substantial depth near one end, a pivot for securing the two arms together at said end near one edge thereof, anchoring means on one arm at said end near the other edge thereof, and anchoring means on the other arm remote from said end of greater depth, said anchoring means being disposed to receive a pressure applying device for applying a force longitudinally of said arms for moving the unpivoted ends of the arms outwardly relative to each other substantially at right angles to the direction of said applied force.
2. In a device for pushing and straightening panels, a pair of channel-shaped arms of substantial depth near one end, a pivot for securing the two arms together at said end near one edge thereof, anchoring means on one arm at said end near the other edge thereof, anchoring means on the other arm remote from said end of greater depth, said anchoring means being disposed to receive a pressure applying device for applying a force longitudinally of said arms for moving the unpivoted ends of the arms outwardly relative to each other substantially at right angles to the direction of said applied force, and universally mounted plates secured to the unpivoted ends of said arms.
